UNITED STATES PATENT OFFICE

CLEMONS C. CROSBY, OF BELMOND, IOWA

DECAPPER FOR BOTTLES

Application filed May 20, 1929. Serial No. 364,560.

This invention aims to provide a simple means whereby a bottle cap may be removed from a bottle, the construction being such that the decapping means will be accessible from all sides.

It is within the province of the disclosure to improve generally and to enhance the utility of devices of that sort to which the invention appertains.

10 With the above and other objects in view, which will appear as the description proceeds, the invention resides in the combination and arrangement of parts and in the details of construction hereinafter described and claimed, it being understood that changes 15 in the precise embodiment of the invention herein disclosed may be made, within the scope of what is claimed, without departing from the spirit of the invention.

20 In the accompanying drawings:—

Figure 1 shows in side elevation, a device constructed in accordance with the invention;

Figure 2 is a vertical section wherein parts are in elevation;

25 Figure 3 is a bottom plan, the standard being in section.

The device forming the subject matter of this application preferably is made of metal throughout. It includes a standard 1 and a 30 head 2 threaded on the upper end of the standard 1. The head 2 is provided in its lower end with a recess 3 defining a circumferentially-continuous flange 4. The cap 6 of a bottle 7 may be engaged with the flange 4, the 35 flange forming a shoulder, as shown at 5 in Figure 2, the lower portion of the cap 6 resting against the standard 1, as shown in Figure 2. If the bottle 7 is swung downwardly from the position of Figure 2, the shoulder 5 40 will remove the cap 6 in a way which will be understood readily when Figure 2 of the drawings is noted.

Because the flange 4 is circumferentially-continuous, a bottle cap may be removed at a 45 point anywhere around the standard 1. It is possible for several persons to stand around the device and remove caps, one article, thus, serving for the accommodation of several persons who are removing bottle caps at the 50 same time. The lower end of the standard

1 is anchored or secured in any preferred way. A lock nut 8 is threaded on the standard 1 and is housed within the recess 3, the lock nut engaging the head 2, within the recess 3, to prevent the head 2 from rotating, and to hold the head on the standard 1.

The construction of the device is such that it may be placed on the gear shift lever of an automobile, the head 2 becoming a handle whereby the gear shift lever is operated. Under such circumstances, a person sitting in the automobile has a convenient but inconspicuous means at hand whereby a cap can be removed from a bottle.

What is claimed is:—

1. A bottle opener comprising a standard, a head on the upper end of the standard, the head being provided in its lower end with a recess defining a circumferentially continuous flange constituting a shoulder which, co-operating with the standard, forms a means whereby a bottle cap may be removed at a point anywhere around the standard and the head and means for securing the lower end of the standard, thereby to maintain the standard anchored in an approximately vertical position.

2. A bottle opener comprising a standard, a head threaded on the upper end of the standard, the head being provided in its lower end with a recess defining a circumferentially continuous flange constituting a shoulder which, co-operating with the standard, forms a means whereby a bottle cap may be removed at a point anywhere around the standard and the head, and a lock nut threaded on the standard and engaging the head within the recess.

In testimony that I claim the foregoing as my own, I have hereto affixed my signature.

CLEMONS C. CROSBY.
